PRESSURIZED DISPENSING CAN

Thomas B. Aldrich III, Bronx, N.Y., assignor to The Proctor & Gamble Company, Cincinnati, Ohio, a corporation of Ohio

Filed Apr. 4, 1963, Ser. No. 74,306

Term of patent 14 years

(Cl. D58—17)

FIG. 1 is a rear elevational view of the upper portion of a pressurized dispensing can showing my new design.

FIG. 2 is a front elevational view thereof, with portions broken away to show indeterminate length.

FIG. 3 is a side elevational view of the upper portion of the same as seen from the right of FIG. 1.

FIG. 4 is a top plan view of the same.

I claim:

The ornamental design for a pressurized dispensing can, as shown and described.
